PHOTOGRAPHIC CAMERA

Peter Tighe Quinn, Rochester, N.Y., assignor to Eastman
Kodak Company, Rochester, N.Y., a corporation of
New Jersey

Filed Feb. 14, 1966, Ser. No. 1,039

Term of patent 14 years

(Cl. D61—1)

FIG. 1

FIG. 2

FIG. 3

FIG.4

FIG.5

FIG.6

FIG.7

FIG.8

FIG.9

FIG. 10

FIG. 11

FIG. 12

FIG. 1 is a top plan view of a photographic camera, showing my new design;

FIG. 2 is a front elevational view thereof;

FIG. 3 is a bottom plan view thereof;

FIG. 4 is a left-side elevational view thereof;

FIG. 5 is a right-side elevational view thereof;

FIG. 6 is a rear-elevational view thereof;

FIGS. 7-12 correspond to FIGS. 1-6 respectively, but show the objective carrier and shutter release extended to their picture taking positions.

I claim:

The ornamental design for a photographic camera, as shown.
